UNITED STATES PATENT OFFICE.

JONATHAN BARTLETT, OF EPPING, AND GEORGE B. WIGGIN, OF SOUTH NEW MARKET, NEW HAMPSHIRE, ASSIGNORS OF ONE-HALF TO JOHN W. HOARD, OF PROVIDENCE, RHODE ISLAND.

SEWING-MACHINE.

SPECIFICATION forming part of Letters Patent No. 399,818, dated March 19, 1889.

Original application filed July 28, 1887, Serial No. 245,561. Divided and this application filed May 3, 1888. Serial No. 272,747.
(No model.)

To all whom it may concern:

Be it known that we, JONATHAN BARTLETT, of Epping, and GEORGE B. WIGGIN, of South New Market, in the county of Rockingham and State of New Hampshire, have invented 5 certain new and useful Improvements in Sewing-Machines; and we do hereby declare that the following is a full, clear, and exact description of the invention, which will enable others skilled in the art to which it appertains to make and use the same, reference being had to the accompanying drawings, and to letters of reference marked thereon, which form a part of this specification.

15 Our invention relates to sewing-machines generally, but more particularly to the class of waxed-thread machines adapted for sewing shoes or other articles made from leather or other kindred material, but has more es- 20 pecial reference to the construction of the work-supporting device, or what is usually called the "horn," and to the construction and action of parts adjacent thereto.

In the accompanying drawings, Figure 1 is 25 a side elevation of the horn and thread-looper; Fig. 2, a front view of the same, and Fig. 3 a plan view of the angle-piece on top of the horn.

Our improved horn or work-rest is shown in 30 Figs. 1, 2, and 3 in its relation to adjacent parts. The horn has on its top a loosely-piv- 35 oted right-angled tongue or lip, 1, whose upper edge is adapted to project into a slit cut in the sole of a shoe or other piece of leather, and a small notch, 2, in the base of this right-angled piece permits the piece to have a slight 40 swinging movement on its center or pivot 3, which is restricted by a fixed pin, 4, in the horn. This lateral play or swing allows the 45 tongue 1 to accommodate itself to the curves or sinuosities of the sole when sewing, and especially at its hollow or shank part. When sewing around certain convex parts—such as the heel of the boot or shoe—the position of the tongue (see Fig. 3) is rigid, inasmuch as one side of the slot 2 then bears continually against this pin, the tongue being turned slightly to one side, and without this turning the curves would not be so truly and readily

rounded. The horn at its upper end rests on 50 and forms an arch with an upright portion or plate, 5.

With this form of horn and its swinging tongue 1 we prefer to use the crank-shaped and tubular thread looper or carrier v^4 and post n^2 , pinion n' , and supporting-sleeve n^3 , substantially as shown. The pinion n' engages with a concave instead of with a convex rack; but these looping devices form the subject-matter of an independent application, 60 Serial No. 272,746, filed May 3, 1888.

Referring now to the drawings, which show our improved form of horn in its relation to our preferred looping devices, the position of the parts is shown at that stage of the sewing 65 after the needle has just caught the thread and is carrying it through the sole of the shoe. The arrow near the lower part of Fig. 1 shows the direction or route of the thread from the wax-pot, which, as usual, is located below the 70 machine, and the upper arrow shows the direction of the needle-feed movement.

Our machine can be used for sewing almost any material; but it is more particularly adapted for sewing shoes, either turned or 75 welted, the narrow edge afforded by the horizontal top v^2 of the horn W being particularly adapted for welted goods.

This application being one of the divisions of our original application filed July 28, 1887, 80 Serial No. 245,561, we do not herein claim anything claimed either in that application or in either of the other division applications, Nos. 272,745 and 272,746, both filed May 3, 1888

85

We claim—

The improved horn and rest described, the rest being a pivoted angled piece, 1, having an opening at the rear of its base and the horn having a fixed pin projecting into such opening, which opening is larger than the body of the pin and serving to limit in both directions the swinging movements of such rest.

JONATHAN BARTLETT.
GEORGE B. WIGGIN.
